UNITED STATES PATENT OFFICE.

JULIUS BRENZINGER, OF FAIRFIELD, CONNECTICUT, ASSIGNOR TO THE MAX AMS MACHINE COMPANY, OF BRIDGEPORT, CONNECTICUT, A CORPORATION OF NEW YORK.

MACHINE FOR SHAPING SHEET MATERIALS.

Application filed September 30, 1921. Serial No. 504,410.

To all whom it may concern:

Be it known that I, JULIUS BRENZINGER, a citizen of the United States, and a resident of Fairfield, in the county of Fairfield and State of Connecticut, have invented certain new and useful Improvements in Machines for Shaping Sheet Materials, of which the following is a specification.

This invention relates generally to a machine for flanging, beading, or otherwise shaping, by pressure, bodies of sheet material and has more particularly reference to a machine for producing, by pressure, a knurled portion and a thread in a previously formed cap of sheet material, the character of the cap being that usually employed in connection with bottles for containing chili sauce or catsup. While the shaping of a cap of this character is one of the objects of this invention, it will be understood that, so far as certain features of the invention are concerned, the character of the body and the shape to be imparted to it is immaterial.

The main object and feature of the invention is the production of a machine for quickly and efficiently shaping previously formed bodies of sheet material while coming in a constant stream from a hopper or from a body-forming or other machine, the bodies being fed automatically to the machine, properly positioned therein with respect to the shaping tools, shaped while traveling through the machine and finally automatically stripped or delivered. In this manner a greatly increased production is obtained.

Other features of the invention will appear as the specification proceeds.

In the accompanying drawings, the invention is embodied in a concrete and preferred form in which:

Figure 1 is a front elevation of a machine embodying the invention:

Fig. 2 is an end elevation, partly in section on the plane of line 2-2 of Fig. 1:

Fig. 3 is a horizontal sectional view on the plane of line 3-3 of Fig. 1:

Fig. 4 is an irregular vertical sectional view substantially through the center of the machine on the plane of line 4-4 of Fig. 1:

Fig. 5 is a vertical sectional view on the plane of line 5-5 of Fig. 1 showing more particularly the shaping head:

Fig. 6 is a vertical sectional view on the

plane of line 6-6 of Fig. 1 showing more particularly the feeding head:

Fig. 7 is an irregular sectional view on the plane of line 7-7 of Fig. 4:

Fig. 8 is a detail sectional view on the plane of line 8-8 of Fig. 4 showing the body being shaped by the tools: and

Fig. 9 is a view similar to Fig. 8 showing the body after it has been shaped and stripped from the shaping tools.

The product of the machine is shown in Figs. 8 and 9 where, at 1, a cap is indicated having, at one end, a closed head 2. During its passage through the machine, one portion of the cap is knurled, as at 3, and another portion is provided with a thread, 70 as at 4.

The machine as here shown comprises two heads 5 and 6 arranged side by side and rotating, either step by step or continuously, in unison and preferably continuously, between which the body to be shaped is fed, as by means of a chute 7 (Fig. 4), and from which it is delivered, as by means of chute 8. The shaping tools comprise here a stationary member 9 and one or more rotatable members 10 (Fig. 8). The stationary member 9 acts on the outer periphery and rotatable member 10, which is here a body-receiving member, on the inner periphery of body 1: and it will therefore be understood that the inside tool 10 must either be given a movement projecting it within the body or else the body itself must be given a movement projecting it over the inside tool. In cases where the body being acted upon is open at both ends and the inside tool is projected within the body, both of the rotating heads may carry tools so as to act upon both ends of the body. In the present instance, one end of the body is closed and it is preferred to move the body transversely over the inside tool.

This transverse movement may conveniently be, and here is, effected by mechanism carried by the rotating head 5, and this head may therefore be called a feeding head. The other head 6, carrying the tools, we may term a shaping head. Any suitable means may be used to rotate the two heads, such as gears 11 and 12, carried by the heads, and pinions 13 and 14 carried by a power shaft 15, the heads being loosely mounted on a stationary shaft 16.

The feeding head 5 carries a body supporting member 17 bolted thereto (Fig. 7) or to gear 11 carried thereby; and this member 17 is in alignment with chutes 7 and 8 and consists of a central portion 18 (Figs. 4, and 7) having a number (here four in number) of pockets 19, and having cheek plates 20. During rotation of the heads, bodies 1 coming from chute 7 fall into pockets 19, and in alignment, transversely, with these pockets are shaping tools 10, carried by the shaping head, and reciprocating member 21, carried by the feeding head. These reciprocating members serve to move the bodies from pockets 19 into position on tools 10 and also to strip the bodies from said tools in a manner to be explained. The construction of these reciprocating members is as follows: the feeding head is provided with four guides 22 (Fig. 6) and in each of these guides is a slide 23 actuated by means of a stationary cam 24, in which latter travel cam rollers 25 connected with the slides. It will be understood from the foregoing that the revolution of the feeding head causes transverse reciprocation of slides 23. Each of said slides carries a spring seated plunger 26, the outward movement of which is limited by stop member 27 acting against abutment 28. Surrounding the outer end of plunger 26 is a sleeve 29 and extending out through the end of said sleeve is a stem 30 having a presser head 31. At its inner end, said stem carries a ball-shaped head 32 bearing against anti-friction balls 33 seated in plunger 26, this construction being provided to admit of easy rotation of the presser head 31 when pressing the body over rotating shaping tool 10. Sleeve 29 is further provided with a yoke having two rods 34 that extend through the central portion 18 and cheeks 20 of the body supporting member 17 and carry the stripper member 35 (Figs. 3, 4, 8 and 9) surrounding the shaping tool 10.

The shaping head carries as supports for the shaping tools 10, a series of spindles or shafts 36 (Figs. 3, 4, 5 and 8), each of which is mounted in two bearings 37 and 38, the latter being pivotally supported at 39 and the former slidably supported in boxes 40. By means of set screw 41 and lock nut 42, the bearing 37 may be adjusted, this movement being permitted by pivotal bearing 38. By these means, each shaping tool 10 may be adjusted with respect to the shaping tool 9; and, to admit of slight yielding in the pressure of shaping tool 10, there is interposed a strip 43 of leather, or other material, between box cap 44 and bearing 37.

Any suitable means (Figs. 1, 2 and 3) may be used to rotate spindles 36 and the shaping tools 10 carried thereby. In the present instance, each spindle 36 is provided with a pinion 45 engaging with a central pinion 46

moving with gear 47 loosely mounted on stationary shaft 16. Gear 47 derives its motion from gear 48 mounted on countershaft 49, said countershaft carrying a gear 50 meshing with gear 51 on power shaft 15. At its outer end each spindle 36 carries a shaping tool 10, here composed of a threaded member 52, (Figs. 3, 4, 7 and 8) keyed to spindle 36 and a knurled member 53 loosely mounted on spindle 36 and held in place by end member 54 tapped into said spindle.

Shaping tool 9 (Figs. 4 and 8) consists of two curved or segmental members 55 and 56, the former knurled and the latter threaded and both mounted stationary on fixed shaft 16 and located in the plane of tool 10, that is at one side of the plane of supporting member 17 and chutes 7 and 8.

A body arriving from chute 7 drops into a pocket 19 of body-supporting member 17 and, during rotation of the parts, slide 23 pushes the body on shaping tool 10 and, as the latter travels over segments 55 and 56, the body is properly shaped between the members 9 and 10. Slide 23 then returns causing stripper 35 to remove the shaped body from tool 10 and thereby depositing it in chute 8 which latter permits it to roll out of the machine.

Threaded member 52 is fast on, and moves with, spindle 36 at a definite speed so that its threads may be synchronized with the threaded member 56, but knurled member 53 is loose so that it may find its own center with respect to knurled member 55.

I claim:

1. In a machine of the character set forth, a stationary shaft, a rotating feeding-head loosely mounted on said shaft, a body-supporting member rotating in unison with and arranged alongside of said feeding head, a slide carried by the feeding head, a cam fixed to the stationary shaft, and connections between the slide and the cam to thereby cause reciprocation of the slide by rotation of the head to move a body of sheet material transversely from the body-supporting member.

2. In a machine of the character set forth, a rotating feeding head, a body-supporting member arranged alongside thereof and rotating in unison therewith, a slide carried by the feeding head, a spring-pressed plunger mounted in said slide, a presser head, free to rotate, connected with said slide and located at the outer end of said plunger, and means for reciprocating said slide to move a body of sheet material transversely from the body-supporting member.

3. In a machine of the character set forth, a rotating feeding head, a body-supporting member arranged alongside thereof and rotating in unison therewith, a slide carried by the feeding head, a spring-pressed plunger

5 mounted in said slide, a sleeve member carried at the outer end of said plunger, a presser head, free to rotate, mounted in said sleeve, anti-friction means carried by the plunger and engaging said freely rotatable presser head, and means for reciprocating said slide to move a body of sheet material transversely from the body-supporting member.

10 4. In a machine of the character set forth, a feeding-head, a body-supporting member and a body-receiving member arranged side by side with the body-supporting member intermediate the feeding head and body-receiving member, means for rotating the body-receiving member around its own axis, a slide carried by the feeding head, a presser head, free to rotate, moving with said slide, and means for reciprocating said slide to cause the presser head to move a body of sheet material from the body-supporting to the rotating body-receiving member.

15 5. In a machine of the character set forth, a feeding head, a body-supporting member and a body-receiving member arranged side by side with the body-supporting member intermediate the feeding head and body-receiving member, means for rotating the body-receiving member around its own axis, a slide carried by the feeding head, a spring-pressed plunger carried by said slide, a presser head, free to rotate, moving with said slide and cushioned by the spring-pressed plunger, and means for reciprocating said slide to cause the presser head to move a body of sheet material from the body-supporting to the rotating body-receiving member.

20 6. In a machine of the character set forth, a body-supporting member, a feeding head and a body-receiving member all rotating side by side in unison, the body-supporting member being intermediate the feeding head and body-receiving member, a transversely reciprocating slide carried by the feeding head, and a presser head carried by said reciprocating slide to move a body of sheet material from the body supporting to the body-receiving member.

25 7. In a machine of the character set forth, a body-supporting member, a feeding head and a body-receiving member all rotating side by side in unison, the body-supporting member being intermediate the feeding head and the body-receiving member, a transversely reciprocating slide carried by the feeding head, a presser head carried by said reciprocating slide on the feeding head to move a body of sheet material from the body supporting to the body-receiving member, a stripper surrounding the body-receiving member, and connections carrying said stripper and extending from the slide through the body-supporting member.

30 8. In a machine of the character set forth, a body-supporting member, a feeding head

and a body-receiving member all rotating side by side in unison, the body-supporting member being intermediate the feeding head and the body-receiving member, means for rotating the body-receiving member around 70 its own axis, a transversely reciprocating slide on the feeding head, and a freely rotatable presser head on said slide to move a body of sheet material from the body-supporting to the body-receiving member.

35 9. In a machine of the character set forth, a body-supporting member, a feeding head and a body-receiving member all rotating in unison side by side, the body-supporting member being intermediate the feeding head and the body-receiving member, means for rotating the body-receiving member around its own axis, a transversely reciprocating slide on the feeding head, a freely rotatable presser head on said slide to move a body of sheet material from the body-supporting to the body-receiving member, a non-rotatable stripper surrounding the body-receiving member, and connections carrying said stripper and extending from the slide through the 90 body-supporting member.

40 10. A machine of the character set forth comprising: two shaping tools, one of segmental shape and relatively stationary with respect to the other for acting on the exterior of a body of sheet material and the other for supporting a body of sheet material and rotatable around its own axis for acting on the interior of said body, and means for advancing the interior tool over 95 the stationary tool.

45 11. A machine of the character set forth comprising: two shaping tools, one of segmental shape and relatively stationary with respect to the other for acting on the exterior of a body of sheet material and the other for supporting a body of sheet material and rotatable around its own axis for acting on the interior of said body, means for advancing the interior tool over the stationary tool, and means for positioning a body of sheet material on the interior tool 105 and for removing it therefrom.

50 12. A machine of the character set forth comprising: a shaping tool to engage with the exterior of a body of sheet material, a shaping tool head, a plurality of shaping tools carried thereby each supporting, and engaging with the interior of, a body of sheet material, and means for revolving the 110 shaping tool head to thereby engage the bodies carried by successive shaping tools of the head with the first-mentioned shaping tool.

55 13. A machine of the character set forth comprising: a shaping tool to engage with the exterior of a body of sheet material, a shaping tool head, a plurality of shaping tools carried thereby each supporting, and engaging with the interior of, a body of 125 sheet material, and means for revolving the 130 shaping tool head to thereby engage the bodies carried by successive shaping tools of the head with the first-mentioned shaping tool.

- sheet material, means for revolving the shaping tool head to thereby engage the bodies carried by successive shaping tools of the head with the first-mentioned shaping tool, and means for rotating the shaping tools carried by the shaping tool head around their individual axes.
14. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, a body-supporting member alongside of and rotating in unison with the shaping tool head to support bodies of sheet material in alignment with the shaping tools carried by said head, and means for feeding a body from the body-supporting member to each shaping tool carried by the shaping tool head prior to the engagement of the shaping tools with each other.
15. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, a body-supporting member alongside of and rotating in unison with the shaping tool head to support bodies of sheet material in alignment with the shaping tools carried by said head, means for feeding a body from the body-supporting member to each shaping tool carried by the shaping tool head prior to the engagement of the shaping tools with each other, and stripper means for removing the bodies from the shaping tools carried by the shaping tool head after the shaping tools have engaged with each other.
16. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, and means for rotating around their individual axes, the shaping tools carried by the shaping tool head, a body-supporting member alongside of and rotating in unison with the shaping tool head to support bodies of sheet material in alignment with the shaping tools carried by successive shaping tools of the head with the first-mentioned shaping tool, and means for feeding a body from the body-supporting member to each shaping tool carried by the shaping tool head prior to the engagement of the shaping tools with each other.
17. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, means for rotating, around their individual axes, the shaping tools carried by the shaping tool head, a body-supporting member alongside of and rotating in unison with the shaping tool head to support bodies of sheet material in alignment with the shaping tools carried by said head, means for feeding a body from the body-supporting member to each shaping tool carried by the shaping tool head prior to the engagement of the shaping tools with each other, and stripper means for removing the bodies from the shaping tools carried by the shaping tool head after the shaping tools have engaged with each other.
18. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, a body-supporting member alongside of and rotating in unison with the shaping tool head to support bodies of sheet material in alignment with the shaping tools carried by said head, a feeding head alongside of and rotating in unison with the body-supporting member, the latter being intermediate the two heads, reciprocating slides carried by said feeding head in alignment with the bodies carried by the body-supporting member to feed bodies from the body-supporting member to the shaping tools carried by the shaping tool head prior to engagement of the shaping tools with each other.
19. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, a

- body-supporting member alongside of and rotating in unison with the shaping tool head to support bodies of sheet material in alignment with the shaping tools carried by said head, a feeding head alongside of and rotating in unison with the body-supporting member, the latter being intermediate the two heads, reciprocating slides carried by said feeding head in alignment with the bodies carried by the body-supporting member to feed bodies from the body-supporting member to the shaping tools carried by the shaping tool head prior to the engagement of the shaping tools with each other, and strippers, for removing the bodies from the shaping tools carried by the shaping tool head after the shaping tools have engaged with each other, mounted on the slides of the feeding head and extending through the body-supporting member.
20. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, means for rotating around their individual axes, the shaping tools carried by the shaping tool head, a body-supporting member alongside of and rotating in unison with the shaping tool head to support bodies of sheet material in alignment with the shaping tools carried by said head, a feeding head alongside of and rotating in unison with the body-supporting member, the latter being intermediate the two heads, reciprocating slides carried by said feeding head in alignment with the bodies carried by the body-supporting member, and a freely rotatable presser head carried by each slide to feed bodies from the body-supporting member to the shaping tools carried by the shaping tool head prior to the engagement of the shaping tools with each other.
21. A machine of the character set forth comprising: a shaping tool to engage with the exterior of a body of sheet material, a shaping tool head, a plurality of shaping tools carried thereby each supporting and engaging with the interior of a body of sheet material, means for revolving the shaping tool head to thereby engage the bodies carried by successive shaping tools of the head with the first-mentioned shaping tool, means for rotating, around their individual axes, the shaping tools carried by the shaping tool head, a body-supporting member alongside of and rotating in unison with the shaping tool head to support bodies of sheet material in alignment with the shaping tools carried by said head, a feeding head alongside of and rotating in unison with the body-supporting member, the latter being intermediate the two heads, reciprocating slides carried by said feeding head in alignment with the bodies carried by the body-supporting member to feed bodies from the body-supporting member to the shaping tools carried by the shaping tool head prior to the engagement of the shaping tools with each other, and strippers, for removing the bodies from the shaping tools carried by the shaping tool head after the shaping tools have engaged with each other, mounted on the slides of the feeding head and extending through the body-supporting member, the latter being intermediate the two heads, reciprocating slides carried by said feeding head in alignment with the bodies carried by the body-supporting member, a freely rotatable presser head carried by each slide to feed bodies from the body-supporting member to the shaping tools carried by the shaping tool head prior to the engagement of the shaping tools with each other, and non-rotatable strippers surrounding the shaping tools carried by the shaping head and carried by the slides of the feeding head and extending through the body-supporting member.
22. A machine of the character set forth comprising: a segmental stationary shaping tool to engage the outer surface of a body of sheet material, a shaping tool rotating around its own axis for engaging the inner surface of said body, means for feeding a body of sheet material transversely of the rotation of the parts into position on the rotatable shaping tool, means for rolling said rotatable shaping tool over the segmental shaping tool, and means for transversely stripping said body from said rotatable shaping tool.
23. A machine of the character set forth comprising: a segmental stationary shaping tool to engage the outer surface of a body of sheet material, a shaping tool rotating around its own axis for engaging the inner surface of said body, means for imparting an uninterrupted unidirectional movement to the rotating shaping tool to thereby roll it over the segmental stationary tool, means for feeding a body of sheet material transversely of the rotation of the parts into position on the rotating tool before it encounters the segmental shaping tool, and means for transversely stripping said body from the rotating tool after it has passed over the segmental stationary tool.
24. A machine of the character set forth comprising: two heads arranged side by side and rotating in unison, a body-supporting member intermediate the two heads and rotating in unison therewith, and means carried by one head for transversely feeding bodies from the body-supporting member to the other head.
25. A machine of the character set forth comprising: two heads arranged side by side and rotating in unison, a body-supporting member intermediate the two heads and rotating in unison therewith, means carried by one head for transversely feeding bodies from the body-supporting member to the other head, and stripper means also carried by said head and extending through the body-supporting member to strip bodies from said other head.
26. A machine of the character set forth comprising: a stationary shaping tool of segmental shape having two surfaces one

formed as the development of a screw thread, and the other knurled to engage the exterior of a body of sheet material; a circular shaping tool to support and interiorly engage a body of sheet material, means for advancing the circular tool over the surfaces of the stationary tool, means for rotating the circular tool, a circular threaded surface on said circular tool and rotating therewith to engage the corresponding surface on the stationary tool, and an independently rotatable, circular and knurled surface also in the circular tool to engage the corresponding surface on the stationary tool.

27. A machine of the character described

comprising: a stationary segmental shaping tool, a rotatable shaping tool head, a plurality of shaping tools carried thereby and successively brought into engagement with the stationary shaping tool by rotation of the head, a shaft supporting each of the shaping tools carried by the head, two bearings for each of said shafts one of them pivotally supported transversely to the axis of the shaft, and means for adjusting the other bearing to cause more or less the shaping tools to engage.

Signed at New York, in the county of New York and State of New York, this 27th day of September, 1921.

JULIUS BRENZINGER.
